(57) **CLAIM**

I claim the ornamental design for a food pan, as shown and described.

DESCRIPTION

FIG. 1 is a top perspective view of the claimed design in a first environment;

FIG. 2 is a right side view of the claimed design of FIG. 1;
FIG. 3 is a left side view of the claimed design of FIG. 1;
FIG. 4 is a front view of the claimed design of FIG. 1;
FIG. 5 is a rear view of the claimed design of FIG. 1;
FIG. 6 is a top plan view of the claimed design of FIG. 1;
FIG. 7 is a bottom plan view of the claimed design of FIG. 1;
FIG. 8 is a top perspective view of the claimed design in a second environment;

FIG. 9 is a right side view of the claimed design of FIG. 8;
FIG. 10 is a left side view of the claimed design of FIG. 8;
FIG. 11 is a front view of the claimed design of FIG. 8;
FIG. 12 is a rear view of the claimed design of FIG. 8;
FIG. 13 is a top plan view of the claimed design of FIG. 8;
FIG. 14 is a bottom plan view of the claimed design of FIG. 8;
FIG. 15 is a top perspective view of the claimed design in a third environment;

FIG. 16 is a right side view of the claimed design of FIG. 15;
FIG. 17 is a left side view of the claimed design of FIG. 15;
FIG. 18 is a front view of the claimed design of FIG. 15;
FIG. 19 is a rear view of the claimed design of FIG. 15;
FIG. 20 is a top plan view of the claimed design of FIG. 15;
and,
FIG. 21 is a bottom plan view of the claimed design of FIG. 15.

The broken lines in the drawings are for purposes of illustrating unclaimed portions of the design. Broken lines formed by equal length dashes show unclaimed portions of the design. Broken lines formed of unequal length dashes (i.e., dash-dot) show boundaries between claimed and unclaimed portions of the design.
